UNITED STATES PATENT OFFICE.

ORTON G. RUST, OF SPRINGFIELD, OHIO, ASSIGNOR OF ONE-HALF TO THEODORE J. REBERT, OF SPRINGFIELD, OHIO.

DISPLAY DEVICE.

1,140,318.

Specification of Letters Patent. Patented May 18, 1915.

Application filed May 29, 1914. Serial No. 841,931.

To all whom it may concern:

Be it known that I, ORTON G. RUST, a citizen of the United States, residing at Springfield, in the county of Clark and 5 State of Ohio, have invented certain new and useful Improvements in Display Devices, of which the following is a specification, reference being had therein to the accompanying drawing.

10 This invention relates to display devices and is designed more particularly for use in displaying charts such as are employed in school rooms and similar places to exhibit exercises, educational matter and information 15 of various kinds.

The object of the invention is to provide a device of this kind upon which a plurality of charts may be mounted in such a manner that they may be shifted from one position 20 to another, thereby enabling different charts to be displayed and also enabling both sides of the same chart to be displayed; to so construct the device that the charts can be moved from one side thereof to the other 25 without removing the same from the hangers and that the supporting devices or hangers for the charts may be adjusted to present either side thereof to the audience without moving the device as a whole; and 30 further, to provide means whereby a selected portion of the matter on a chart may be displayed and other portions thereof concealed from view. It is possible to mount on a device of this kind a series of charts 35 having thereon subjects matter which it is desired to use at different times and to display the desired subjects matter at the desired time without removing any of the charts from the display device.

40 It is a further object of the invention to provide such a device in which the individual charts can be readily placed in position and removed, thereby enabling the charts to be changed to eliminate matter 45 which is no longer needed and to add new matter.

In the accompanying drawings Figure 1 is a side elevation of an apparatus embodying my invention; Fig. 2 is a top plan view 50 of the same; Fig. 3 is a perspective view of one of the hangers and a chart and Fig. 4 is a transverse sectional view of a supplementary device embodying a modified form of the invention.

55 In these drawings I have illustrated one

embodiment of my invention and have shown the same as comprising a pedestal consisting of a base 1 and an upright member or standard 2. Upon the upper end of this standard is a supporting device for 60 the charts preferably comprising a frame 3 having thereon a series of hangers 4. As here shown the frame consists of a longitudinal member rotatably mounted upon the standard 2, and the hangers 4 are pref- 65 erably in the form of rectangular loops of heavy wire or the like, and are rigidly secured midway of the lower portions thereof to the bar 3. This connection may be made in any suitable manner. In the pres- 70 ent instance the bar has been slotted as shown at 5 and the hangers inserted in the respective slots and soldered, thus retaining the same rigidly in an upright position. The hangers are each provided with open- 75 ings to permit the attaching and removal of the charts. The charts are shown at 6 and each is provided along its upper edge with a series of reinforced openings 7. In the present arrangement of the hangers the 80 ends of the bar or wire of which each hanger is formed are arranged near the center of the upper portion of the hangers and spaced apart a distance sufficient to permit the insertion of the edge of the chart, there- 85 by enabling the end of the rod forming the hangers to be inserted through the corre- 90 sponding openings 7 in the chart. This space between the ends of the rod is nor- 95 mally bridged by a ferrule or sleeve 8 which is slidably mounted on the rods and is of such a length that it may be moved beyond the opening to permit the charts to be inserted or removed, or may be moved across the opening to close the same and 100 prevent such insertion and removal. It may be held in adjusted positions in any suitable manner but preferably it is mounted snugly on the rod forming the hanger and will be retained in position by the friction between 100 the same and the rod until force is applied thereto. With this arrangement of the hangers it will be obvious that the charts can be readily transferred from one side of the supporting frame 3 to the other side 105 thereof and that when moved from one side to the other the chart will be reversed, that is, the side which was formerly concealed will be exposed. This permits of the utilization of both sides of the chart, thereby 110

doubling the capacity of the apparatus. I also employ in connection with the display frame a series of screens or "blinders" which may be moved in front of portions 5 of the chart which is on display to conceal parts of the subject matter thereof and to cause only a selected portion or portions thereof to be exhibited. In the present instance I have shown three of these screens 10 which are indicated by the reference numeral 9 in Figs. 1 and 2. In Fig. 1 two only of the screens are in use, these being arranged to exhibit between them a portion only of the chart and to conceal those portions 15 immediately above and below the selected portion, thereby concentrating the attention of the observer or student upon this part of the chart.

As many screens may be employed as is 20 desired or as is necessary to conceal the desired portions of the chart. These screens may be supported in adjusted positions by any suitable means but in the present construction of the device the apparatus is provided with frame members 10 arranged on 25 opposite sides of the standard 2 at the vertical edges of the charts and preferably supported by a frame member or bar 11 rotatably mounted upon the standard 2. The 30 upper ends of these frame members are connected to the horizontal supporting frame 3. This connection may be formed in any suitable manner and as here shown the frame member 3 is made up of two bars arranged 35 close together and having their end portions bent in opposite directions and adapted to extend about the frame members 10 as shown at 12 in Fig. 2. Secured to the inner side of the frame members are guides 13 which co- 40 operate with flanges 14 on the frame members to form guideways 15 in which the screens 9 are slidably mounted. These flanges of the end pieces are provided with a series of holes 16 adapted to receive pins 17 upon 45 which the screens rest and which may be moved from one pair of holes to another to support the screen in adjusted positions. The two bars making up the frame member 3 are here shown as bent outward at the central portion to form a socket 18 in which is 50 rigidly secured a stud 19 which extends into the recessed upper end of the standard 2 and cooperates therewith to form the pivotal connection between the standard 2 and the supporting frame 3. In order that the 55 outermost chart on either side of the frame may be supported close to the screens I have shown the central parts of the lower portions of the several hangers as bent upward 60 so that the bottom wall of the hanger slopes outwardly from the center and on both sides thereof, thereby causing the charts to gravitate toward the outer ends of the hangers and to be supported close to the screens. 65 In connection with the device just de-

scribed I prefer to employ a supplementary device which has in part the function of the main device but further serves as a storage receptacle in which the charts may be stored when not in use. As here shown the supplementary device comprises a cabinet having two parts, one of which constitutes the storage receptacle, as indicated at 20, and the other of which constitutes a display frame, as shown at 21. In this latter part 70 of the cabinet there are provided a series of pins 22 to enter the openings 7 in the charts and to support the charts in a vertical position. The edges of the display portion of the cabinet are extended forwardly and are 75 provided with flanges 23 in which are mounted pins 24 which adjustably support the screens 9 in the same manner and for the same purposes as they are shown in Figs. 1 and 2. The storage receptacle 20 may be 80 of less height than the display portion of the frame and is preferably provided with a door 25 hinged at its lower edge and provided with two or more pins 26 to enter corresponding openings of the charts and support the same in vertical positions when the door is closed. To facilitate the placing of the charts in position on the pins and the removal of the same therefrom I provide means such as a frame 27 having a transverse bar 28 to support the door in a substantially horizontal position with the pins extending upward as shown in Fig. 4. This arrangement enables the charts to be taken from the receptacle, displayed and returned 90 to the receptacle with very little inconvenience.

The construction and use of the apparatus will be readily understood from the foregoing description and it will be apparent that with it a series of charts may be supported and these charts adjusted on the hangers to display a given one of said charts and to display either side of the selected chart, this being accomplished by moving the charts 105 from one side of the supporting frame to the other side thereof and when the desired side of the selected chart has been exposed to view to rotate the supporting frame to place that portion of said chart in a position to be observed by the school or audience. Further, by an adjustment of the screens given portions of the displayed chart may be concealed from view and selected parts thereof may be exposed in such a manner as 110 to concentrate attention thereon. By means of this apparatus the entire chart or any selected part thereof may be exposed or studied or the entire chart may be concealed and it permits of the carrying on the apparatus at one time a yearly feature for daily use such as a morning exercise; a daily or sessional feature such as a quotation or selection of some sort which it is desired to use 115 once only; a periodical feature which it is 120 125 130

desired to use at intervals only, say once a week and any other arrangement or grouping of features, and enables these features to be quickly and easily displayed when desired. Further, the device permits of the ready attaching and removal of the charts, thereby enabling a chart which is no longer needed to be removed and new matter substituted therefor. This interchangeability of the charts gives the device a wide range of utility and enables it to be used for displaying current topics and matters developed by original research as well as for displaying standard exercises, quotations and the like which are used repeatedly.

While I have illustrated one embodiment of my invention, it will be understood that this is chosen for the purpose of illustration only and that I do not wish to be limited to the details of the construction shown and described for obvious modifications will occur to a person skilled in the art.

Having thus fully described my invention, what I claim as new and desire to secure by Letters Patent, is:

1. In a device of the character described, the combination, with a supporting frame, of hangers carried thereby to support a series of charts in a vertical position and having portions forming guides to enable the outermost chart on one side of said frame to be transferred to the outermost position on the opposite side of said frame, without removing any of said charts from said hangers, and a screen adjustably mounted close to the outermost position of the chart on one side of said frame, said hangers having means to cause each chart on said side of said frame to automatically move toward said outermost position.

2. In a device of the character described, the combination, with a supporting frame, of hangers carried thereby to support a series of charts in a vertical position and having portions forming guides to enable the

outermost chart on one side of said frame to be transferred to the outermost position on the opposite side of said frame, without removing any of said charts from said hangers, and a screen adjustably mounted close to the outermost position of said chart on one side of said frame, said hangers having their supporting portions inclined on said side of said frame to cause said charts to move toward said screen.

55

3. In a device of the character described, a pedestal comprising a standard, a frame member secured to the upper end of said standard, hangers secured to said frame members and charts carried by said hangers, other frame members supported by said pedestal, arranged at the vertical edges of said charts and having parts forming guides, a screen extending across the face of said chart and supported in the guideways of said last-mentioned frame members and means to retain said screen in adjusted positions along said guide.

65

4. The combination with a chart, of a display frame therefor having hangers to support said chart in a substantially vertical position, guides arranged at the vertical edges of said charts, screens movably mounted on said guides, and devices for retaining a screen in adjusted positions.

70

5. In a device of the character described, a hanger for supporting charts and the like comprising a loop-shaped member having an opening to permit the charts to be placed on the same and having its lower portion provided with inclined supporting surfaces arranged on opposite sides of the center thereof to cause the charts to move toward the respective ends of said hanger.

75

In testimony whereof, I affix my signature in presence of two witnesses.

ORTON G. RUST.
